UNITED STATES PATENT OFFICE

AARON A. KNEE, OF CHARLOTTE, NORTH CAROLINA, ASSIGNOR TO THE LANCE PACKING COMPANY, OF CHARLOTTE, NORTH CAROLINA

VENDING MACHINE

Application filed September 28, 1928. Serial No. 309,103.

My invention relates to a machine for vending articles which are bound together in ribbon form and provides means for insuring the vending of only one article at a time without injury to the same, together with means for storing a great quantity of the articles to be sold, and with additional spaces for the display of the articles which are dispensed by the machine.

10 An object of my invention is to provide a machine for vending peanuts and comprises means for dispensing bags of peanuts, said peanuts having been secured together in ribbon form, said means comprising mechanism for feeding the ribbon of bags of peanuts to a dispensing apparatus, said dispensing apparatus being adapted to cut off one bag and deliver the same without interfering with the other bags except to advance the same for sale, together with means for holding the ribbon while a bag is being severed therefrom and means for closing the machine after each sale so as to seal the same against the outer atmosphere, thus insuring a fresh stock of peanuts in the container at all times.

I am aware that heretofore peanuts have been sold in bulk form from vending machines, and that machines have been devised for delivering separate bags filled with bulk edibles, but in these structures there is no provision for preventing the outer atmosphere from entering the machine and affecting the flavor of the peanuts and thus rendering these machines useless for the reason that fresh nuts could not be obtained from the machine unless the same had been recently filled.

Another object of my invention is to provide a machine for vending bags of bulk edibles and other articles, which has a base in which the vending mechanism is housed, and which has a transparent top resting on the base, with means associated with the base and projecting in the top for displaying in still position the articles of the type sold, and in addition thereto, the ribbon of articles which is passed thru the vending machine will pass up the back end of the vending machine, then across the top of the machine and then down in front and into the vending mecha-

nism so that the moving articles will be displayed on the top and ends and similar still articles will be displayed on the side portions, so that the entire transparent top will present specimens of the articles sold by the vending machine, which will present a neat appearance and serve as an advertising medium of the goods sold.

Some of the objects of my invention having been stated, other objects will appear as the description proceeds when taken in connection with the accompanying drawings, in which—

Figure 1 is a front elevation of my machine with the front portion of the glass cover cut away;

Figure 2 is a side elevation of my machine, looking from the right in Figure 1, with a section of the glass cover broken away, and other portions cut away for sake of clearness;

Figure 3 is a top plan view of my machine, with a portion of the glass cover cut away;

Figure 4 is a top plan view of the dispensing mechanism;

Figure 5 is a side elevation of the dispensing mechanism looking from the left hand side of Figure 4;

Figure 6 is a side elevation of the dispensing mechanism looking from the right hand side of Figure 4;

Figure 7 is a bottom plan view of the dispensing mechanism showing a portion of the delivery portion cut away;

Figure 8 is a view similar to Figure 5, showing the dispensing mechanism in normal position and with the end disk and spokes omitted;

Figure 9 is a front elevation of the left hand end of the dispensing mechanism, showing the rim and casing cut along the line 9—9 in Figure 8;

Figure 10 is a right hand side elevation of the dispensing mechanism with the end disk and spokes shown in Figure 6 omitted;

Figure 11 is a front elevation of the right hand end of the dispensing mechanism and bears the same relation to Figure 10 that Figure 9 bears to Figure 8;

Figure 12 is a cross-sectional view of the

dispensing mechanism taken along the line 12—12 in Figure 4;

Figure 13 illustrates the form of the ribbon of bags adapted for use in my machine;

5 Figure 14 is a view similar to Figure 8, but showing the parts in raised position just before a bag is severed from the ribbon of bags;

10 Figure 15 is a view similar to Figure 10 and showing the other end of the dispensing mechanism in the same position as shown in Figure 14.

15 Referring more particularly to the drawings, the numeral 10 indicates the base of my machine, which has the parallel upstanding side portions 11 and 12, and the parallel upstanding end portions 13 and 14, said side and end portions having the continuous out-turned flange 15 along their upper edge. The 20 curved housing 16 is disposed in the front portion of the machine and projects rearwardly and downwardly and rests on the base 10, and this housing has the vertically disposed side portions 17 and 18 which rest on 25 a portion of the vending mechanism to be later described so as to shut off the said vending mechanism from the rest of the interior of the machine. There are two longitudinally disposed vertical partitions 19 and 20 which 30 have their forward ends supported by the cover 16 and the remainder of their lower edges rest on the base 10. Secured to the outer sides of these partition members are the 35 corrugated members 21 and 22 which have the vertically disposed pocket members 23 therein in which the bags of peanuts or other articles 24 are supported. On the outer edge of the members 17 and 18 are the shelf members which are adapted to support the bags 40 24. Also secured to the partition members 19 and 20 are the shelves 25 and 26 on which the bags of articles of the type sold by the machine are adapted to be supported for display purposes, said bags being designated by 45 the numeral 27, and at the front and rear ends of the members 21 and 22 the bags 28 are adapted to be positioned vertically, and at the rear ends the bags 29 are likewise positioned, so that when the moving ribbon is 50 mounted in the machine the entire outer upper surface will display the articles to be sold, and in addition, below the shelves 25 and 26 the bags 30 are placed on each side of the machine to complete the display effect, 55 said bags being supported by the shelves 31, one of which is shown in Figure 1, the one on the other side being hidden.

Secured to the outer edges of the housing for the vending mechanism, which are indicated by the reference characters 17 and 18, 60 are the vertically disposed strips 32 and 33, and pivotally mounted on the outer surface of these vertically disposed strips are the arms 34, which have secured in their free ends the cross-wire members 35, and the

70 springs 36 are secured to the strips 32 and 33 and hold these cross-wires in resilient position against the ribbon of bags passing downward to the vending mechanism, which will be later described. Pins 37 limit the backward movement of the springs 36.

Secured to the front end portion 13 are the vertically disposed members 38, 39 and 40, which have their upper portions secured to the cross-bar 41 which has its ends bent 75 backwardly and secured to the inside surfaces of the vertical partitions 19 and 20. This latter arrangement prevents the ribbon of bags from pressing against the glass cover, to be later described.

80 Mounted in the partitions 19 and 20 are the rods 42 and 43 on which the reel members 44 and 45 are loosely mounted. These reel members have the pockets 46 therein in which 85 a bag in the ribbon of bags is adapted to fit as the same is passed over the reels on its travel to the vending mechanism.

Secured between the partition members 19 and 20 and being parallel with the base portion 10, but being disposed in the upper portion 90 of the machine at a point above the rods 42 and 43 and being in alignment with the bottom of the highest pockets on the reels 44 and 45, is the sheet member 47 which is adapted to support the ribbon of bags between the 95 two reels.

100 All of the space below the reels down to the base and to the rear of the vending mechanism housing 16 is adapted to be filled with a continuous ribbon of bags of material 105 adapted to be passed thru the vending machine. This ribbon is denoted by the numeral 48 and the individual bags are designated by the numeral 49. This ribbon is folded on itself back and forth until the 110 said compartment is filled and then it is brought over the rear of the reel 44, as is shown in Figure 2, and then along the top surface of the member 47, then over the reel 45, with the individual bags fitting in the 115 pockets 46, and then the ribbon is passed down in front of the cross-wires 35 and to the rear of the vertical strips 38 and into the vending mechanism to be later described.

120 When the machine is thus assembled and filled, the glass cover 50 is placed over the whole device and it rests on the top of the members 11, 12, 13 and 14, and the lower edge of the glass cover 50 has the outturned flanges 51 thereon which rest against the flanges 15 on the sidewall members 11 to 14, and the strip 52, which is U-shaped in cross-section and hinged at the corners of the cover, as 125 indicated by 53, 54, 55 and 56 in Figure 3, is passed around the machine and locked in position as shown at 57, said locking means comprising the slot 58 in which the rib 59 fits with the bolt 60 passing therethru and the padlock 61 secured in the lower end thereof.

130 It is thus seen that the moving ribbon of

bags 49, the stationary bags 24, 27, 28 and 30 will cause the entire transparent portion of the machine to present the appearance of being packed full of the bags to be sold, while only the moving bags 49 will be sold, the other bags being for display purposes only.

I desire it to be understood that when one ribbon of bags is exhausted that another ribbon of any desired length can be secured 10 to the first ribbon and so on successively, each time the machine is refilled.

I will now describe my vending mechanism which comprises the curved portion 62 which projects backwardly and upwardly 15 into the base portion and has the flat top portion, indicated at 63, and secured to each side of this portion 62 are the vertically disposed portions 64 and 65, which have secured on the top front edge thereof the cover 66 and secured integral with the curved portion of the upper edges of the members 64 and 65 is the circular portion 67, which has integral therewith at each end thereof the extensions which form the rings 69 and 70, 20 said rings having the spokes 71 and 72 with the round bearing portion 73 in the center thereof, and in these bearing portions the rod 75 is adapted to be mounted, which has the handle 76 thereon and on this rod is mounted 25 the tubular member 77 on which a reel member 78 is adapted to rotate. This reel member 78 is similar to the reel members 44 and 45 previously described, and has the same number of pockets 79 therein in which the 30 bags of articles adapted to be vended are adapted to fit as they pass through the vending machine. This reel member comprises the tubular member 80 which is mounted on the tubular member 77 and has the spoked members 81, 82, 83 and 84 mounted thereon with the ends of the spokes 81 and 82 being joined by members 85 and the ends of the spokes 83 and 84 are joined by the members 86, thus forming the pockets 79 therebetween.

Secured to the tubular member 80 and integral therewith, as well as the spoke members, are the disk members 87 and 88, the disk member 88 being a plane disk member, while the disk member 87 has the circular laterally 45 projecting portion 90 thereon which has five slots 91, 92, 93, 94 and 95 therein, the purpose of which will be later described. The mechanism just described is mounted on and entirely supported by the tubular member 77, 50 which tubular member stops flush with the outer edge of the portion 90 at one end, but projects outwardly beyond rim 70 on the other end.

Contiguous to the outer surface of the disk 55 88 is the member 96 which is loosely mounted on the tubular member 80, and to the lower end thereof in Figure 14 is secured the knife member 97 which extends all the way across and is secured to the member 98 60 on the other end of the mechanism, which

will be later described. This knife member 97 travels in close proximity to the circular portion 67 and on one side thereof has the knife edge 99 and on the other side thereof has the dulled portion 100, which is adapted to pass up underneath the ribbon of merchandise on its backward travel without injuring said merchandise. These members 96 and 98 project rearwardly in the form of the extensions 101 and 102 and have secured to the lower edge thereof the closure member 103, which has the rubber or felt gasket 104 thereon which is adapted to fit against the upper edge 63 of the delivery chute. The member 96 has the eccentrically mounted cam 105 thereon, the purpose of which will be later described, but this cam is integral with the member 96. The member 98 is circular and has the two arc-shaped cavities 106 and 106^a therein, and has pivotally mounted on its inner surface the bent lever 107 which lever is pivotally mounted as at 108 and has the projection 109 thereon and has the lateral projecting member 110 thereon and at the end thereof has the lateral projection 111, the projection 110 projecting out into and traveling in the slot 106, while the projection 111 projects out into and travels in the slot 106^a. This lever 107 is mounted in the same plane as the projecting rim 90 on the member 87. Secured to the projection 111 is the double acting tension spring 112, which is secured at its other end to the pin 113^a in the member 69. The member 69 has the inturned arc portion 113, which is indicated in Figures 6 and 10, against the outer edge of which the projection 110 is adapted to slide in one direction of travel.

Secured on the outer surface of the curved portion 67 and in close proximity to the ring portion 69 is the leaf spring 114 which has secured thereto the dog 115 which projects inward through the hole in the portion 67 so as to press against the outer edge of the circular portion 90 and whose end is adapted to fit into the slots 91 to 95 in said circular portion. The outer surface of the member 98 has secured thereon the eccentric cam 105—^a, which is similar to the cam 105 on the member 96, and on these eccentric cams 115 I mount means for holding the ribbon of bags in position while a bag is being cut therefrom for delivery by the vending machine. On the member 98 and surrounding the cam 105—^a is the member 115 which projects outwardly and at the outer end thereof has the blade 116 mounted thereon, which blade is shown in raised position in Figures 14 and 15, but which is shown in closed position in Figures 8 and 10. This blade extends across the device and has its other end connected to the member 117 which is similar to the member 115, and which member is mounted on the eccentric cam 105 and a pin 118 is secured in the member 117 around which is 120 125 130

secured the spring 119, which is wrapped around the bearing center and has its other end secured to a pin 120 mounted in the spoke 71. The purpose of this spring 5 is to return the blade 116 and associated parts quickly to lowered position. The member 117 has the slot 121 therein and above this slot a pin 122 pierces said member and acts as a pivotal point for the dog 123, which 10 has an inturned projection 124 working in said slot and when the blade is in lowered position the projection 124 is adapted to fit into the notch 125 in the member 96 and lock the blade 116 and members 117 and 15 115 and associated parts to the members 96 and 98, but on the inner surface of the ring 70 there is a sloping cam 127 against which the end of the dog is adapted to slide on the upward travel of the closure mechanism and 20 the blade mechanism, the purpose of said cam being to dislodge the projection 124 from the notch 125 and the spring 119 will cause the blade and associated parts to fall quickly under the tension of said spring and 25 to occupy a position as shown in Figures 8 and 10, said blade fitting on the inside of the delivery portion and fitting over the edge of the arc portion 67, which will catch the ribbon of bags at a point approximately mid- 30 way between the bags between the said blade and the arc portion 67 and hold the same while the knife 99 moves upward to sever the end bag from the ribbon on the inner surface of the arc portion 67. In the lower- 35 most portion of the blade 116 and associated parts, the upper end of the dog 123 will be held behind the cam 130 and as the closure mechanism is lowered, after the end bag has been severed, the eccentric cams 105 40 and 105—a will cause the blade to be lifted up slightly and then pulled backward out of the path of travel of the inner edge of the closure member 103 which is due to the fact that the pins 120 and 120—a in the members 70 and 69 respectively will prevent fur- 45 ther downward travel of the members 117 and 115 and will cause them to be raised upwardly slightly and then pulled backwardly to cause the blade 116 to move inwardly out 50 of the path of the inner edge of the closure member. The projections 101 and 102 have mounted therein the rod 131 which has secured thereon the fingers 132, 133 and 134, which fingers fit between and at the ends of 55 the spoke members 81 to 84, and on the left hand end of the vending mechanism, as seen by an observer standing in front of the machine, and which is best illustrated in Figure 14, there is fixedly secured the L-shaped 60 lever 133 whose portion 134 normally lies flush against the outer surface of the ring member 70, as shown in Figure 5. When the closure device is in lowered position and 65 when the lever 76 is operated to cut off and deliver a bag, and the closure 103 is raised,

the lever 133 will strike the elongated cam 135 on the ring member 70 and this will cause the members 132, 133 and 134 to move backwardly between the reel members into an adjacent pocket and push the end bag of merchandise backwardly so that it will fall down into the upper end of the delivery chute ready for the blade 116 to impinge itself thereon and hold the same for the upper advancement of the knife 99. 70

Secured to this rod 131 is the coiled spring 137 which projects forwardly and rests on the upper inner edge of the closure member 103 to prevent rotation of the spring, the purpose of the spring being to return the pusher members 132, 133 and 134 back to normal position, as shown in Figure 4, they being in the position in Figure 15 and being in their natural position in Figures 5 and 6 as well as in Figure 4. 80

The purpose of the cam 130 is to hold the blade to keep the same from being raised and to cause the members 115 and 117 to travel along the top edge of pins 120 and 120—a, which will cause the blade to be drawn inwardly toward the center of the reel and in this way the dog 123 will be released from engagement with the cam 130. 90

The rod 75 is of reduced size along the portion which is within the tubular member 77, but is enlarged after leaving this tubular portion and the cam 105—a has a squared opening therein in which a squared portion of the rod 75 fits, which causes the closure mechanism to move at all times with the rod 75 and the lever 76 and a coiled spring 139 is secured to the rod at one end thereof by means of the cuff 140, and the other end of the said coiled spring is secured to the spokes 72 in any suitable manner so as to cause built up energy in the spring, while the closure mechanism is being raised to cause the rod and closure mechanism to be returned to normal position. 100

The ring 69 has the projection 141 thereon against which the member 102 is adapted to move to limit the upward swing of the closure mechanism, and which also limits the path of travel of the vending mechanism. 110

Standing in front of Figure 1 and observing Figures 10 and 15 we will note that when the lever is in normal position and the closure mechanism and vending mechanism is in normal position, that a forward pull on the lever will cause the reel to be advanced forwardly or in a counter-clockwise direction in Figures 10 and 15, it would be noted that the projection 109 is fitting in the slot 93, which prevents the dog 115 from entering such slot and thus the closure mechanism and the reel mechanism are locked together, due to the fact that the bent lever 107 is mounted on the closure mechanism and the slot 93 is a part of the disk at the right hand end of the reel looking from the front, and this will cause the closure mechanism and the reel mechanism to travel 120

75

80

100

105

110

115

120

125

130

together, and digressing for a moment to the other end of the mechanism the projection 124 will be seated in the slot 125 due to the inward pull of the spring 142, which is secured at one end to the pin 143 on the member 117 and has its other end secured in the dog 123, as at 144, and the blade mechanism will also be locked to the closure mechanism so that all three mechanisms will be raised at the same time and the projection 110 will travel on the outer surface of the arc member 113, and this arc member being stationary, the projection 110 will travel forwardly and downwardly until it passes the lower end of the arc member 113 at which time the parts will occupy a position approximately as shown in Figures 14 and 15, or a little higher position as these figures are shown just as the release takes place and just before the upper end of travel of the said mechanism, the cam 133 will engage the projection 135 (see Figure 14) and the push members 132 to 134 will be pushed outwardly to the position shown in Figure 15 to cause the end bag of peanuts to fall over to the dotted line position shown in Figure 15 and a slightly further upward travel will cause the dog 123 to engage the cam 127 and release the projection 124 from the notch 125 (see Figure 14) and the blade 116 and associated parts will be released from the other mechanism and will fall to the position shown in Figure 10 and the upper end of the dog 123 will catch behind the cam 130 and the blade 116 will be held in a rigid position, and then when the mechanism is moved upward slightly further the projection 110 will pass the lower end of the arc member 113 and the built up energy in the spring 127 will pull it to the position shown in Figure 15 and the locking mechanism between the reel mechanism and the closure mechanism will cease, due to the projection 109 leaving the slot 93, and the end of the dog 115 will take a position in the next succeeding slot 92 and will lock the reel against further movement, but the closure mechanism will continue to be raised upwardly and at this point of operation the severing knife 99 will come up into the path of the ribbon of bags and sever the last bag on the ribbon from the ribbon while it is still held by the blade 116, and then the lever 76 will be released and the spring 39 will cause the said lever 76 and the closure mechanism to return to normal position, as shown in Figures 8 and 10, and while this lowering operation is proceeding the plate 116 will be raised upwardly and pulled inwardly by the combined actions of the pins 120 and 120—a and the eccentric cams 105 and 105—a as previously described.

It is thus seen that I have provided a vending machine capable of vending a ribbon of merchandise, having means for feeding said ribbon of merchandise through the machine and delivering one article at a time to a given

point and hold the article while the end article is severed from the ribbon, together with means which will automatically close and hermetically seal the inside of the container from the outer atmosphere, as the only air can reach the container will be through the delivery portion 145 in the front portion 13 of the machine.

In the drawings and specification I have set forth a preferred embodiment of my invention, and although specific terms are employed, they are used in a generic and descriptive sense only, and not for purposes of limitation, the scope of the invention being set forth in the appended claims:

I claim:

1. In a vending machine, a framework, a base portion, longitudinally and vertically disposed partitions on the framework, means on the exterior of the said partitions for holding objects, a glass cover for the framework and being adapted to rest on the base portion, means in the top of the framework for supporting a plurality of joined objects and allowing the same to be advanced with respect to the framework, vending mechanism mounted in the forward end of the base portion to which said joined objects are adapted to be fed, said vending mechanism comprising means for advancing the joined objects thru the said mechanism and for separating one of the joined objects at a time from the others and delivering the same to the exterior of the machine.

2. In a vending machine, a base portion, a vending mechanism mounted in the base portion, said vending mechanism comprising a delivery portion communicating with the exterior of the base portion, a reel mounted above the delivery portion, a closure for the upper end of the delivery portion, means for opening the closure and advancing the reel as a unit, and means for causing the closure to retrace its path without changing the position of the reel.

3. In a vending machine, a rod having a lever thereon, a reel mounted on the rod, and being adapted to advance a ribbon of articles thru the vending mechanism, a delivery portion, a closure for the delivery portion mounted on the said rod, means for locking the reel and the closure together for movement in one direction, means for terminating this connection while the said parts are advancing together, and means for severing an article from the ribbon while the said closure is still advancing and after the reel has stopped, and means for returning the closure to normal position.

4. In a vending machine, means for advancing a ribbon of spaced articles thru a vending mechanism, said vending mechanism comprising a rod having an operating lever secured to one end thereof, a tube mounted on the rod, a reel member having a plurality

of pockets therein and being mounted on the tube, a delivery portion, a closure for the upper end of the delivery portion, said closure means being mounted on the tube; a blade member having its supports mounted on the outer sides of the closure means, means for locking the closure means, the reel and the blade together for unitary movement, and means for releasing the said object from each other in sequence.

5. In a vending machine adapted to vend bags of bulk edibles, said bags being secured to a continuous strip of flexible material, a framework having means therein for storing and feeding a ribbon of bags to the vending mechanism, said vending mechanism comprising a reel member for advancing the ribbon of bags thru the machine, a delivery portion thru which the bags are vended, a closure 15 for the delivery portion, a knife cooperating with the closure, said means being adapted to cooperate to advance the ribbon of bags thru the vending mechanism, to open and close the closure, to sever one bag at a time 20 from the ribbon, and to hold the said bag while it is being severed from the ribbon.

6. In a vending machine, a dispensing mechanism comprising a transversely disposed rod, a rotatable tube mounted on the rod, a lever secured to the rod, a reel having a plurality of pockets therein and being secured to a second tube which is rotatably mounted on the first tube, a delivery spout, a closure mechanism for the upper end of the delivery spout, said closure mechanism being mounted on the said first tube, a blade mechanism integral with the closure mechanism, and means for locking the reel and the closure mechanism together for rotation in 35 one direction, and means for releasing the closure mechanism from the reel to allow it to continue its rotation and to retrace its path without moving the reel.

7. In a vending machine, a framework, a plurality of reels mounted in vertically disposed spaced partitions, said partitions forming a storage compartment for articles to be vended by the machine, means for leading and propelling a continuous strip over 40 the reels, said strip being adapted to support a plurality of spaced articles to be sold by the machine, a vending mechanism mounted in the framework, a delivery portion leading from the vending mechanism to the exterior of the machine, and means for normally closing the delivery portion, and means for opening the delivery portion for delivery of an article from the vending machine.

8. In a vending machine adapted to vend articles secured in spaced relation to each other to a strip of flexible material, comprising a reel rotatably secured on a transversely disposed rod, a plurality of pockets 55 in the reel in which the articles to be vended

are adapted to fit, circular disk members secured on the ends of the reel, a circular rim member integral with the outer portion of one of the disks, a plurality of cutaway portions in the said rim, closure operating members mounted on the rod and adapted to rotate therewith, a delivery spout positioned beneath and rearwardly of the reel, a closure member mounted on the ends of the closure operating members, a knife mounted on the other end of the closure operating members, means for holding an article while the same is being severed by said knife, a spring pressed dog mounted on one of the closure operating members and being adapted to fit 75 into one of the cutaway portions, a second spring pressed dog mounted on the delivery spout portion and being adapted to also fit into one of the cutaway portions, means for selectively causing one of the dogs to fit in 80 one of said slots to lock the reel and closure together for unitary movement, and to release the said reel and closure member from each other.

9. In a vending machine, a vending mechanism comprising a reel member, a closure operating member, a blade member, a delivery spout adapted to be normally closed by the closure operating member, means for locking the reel member, the closure operating member and the blade member together for unitary movement in one direction, and means for releasing the blade member, then releasing the closure member from the reel member, and means for returning the closure member to normal position.

10. In a vending machine, means for dispensing articles from a plurality of articles secured to each other in spaced relation, said means comprising a reel for passing the articles thru the machine, a knife for severing one article at a time from the other articles, a delivery spout thru which the severed article is adapted to fall, closure means for normally closing the delivery spout, and means for opening the delivery spout, then advancing an article thereabove, then holding the articles while the article is severed from the others, then severing the article, then closing the delivery spout.

In testimony whereof I affix my signature.

AARON A. KNEE.
